UNITED STATES PATENT OFFICE.

HYMAN COHEN, OF BROOKLYN, NEW YORK.

GAITER.

No. 897,714.

Specification of Letters Patent.

Patented Sept. 1, 1908.

Application filed March 19, 1907, Serial No. 363,169. Renewed June 19, 1908. Serial No. 439,454.

To all whom it may concern:

Be it known that I, HYMAN COHEN, a subject of the Czar of Russia, and residing at Brooklyn, in the county of Kings and State of New York, have invented certain new and useful Improvements in Gaiters, of which the following is a specification, such as will enable those skilled in the art to which it appertains to make and use the same.

10 This invention relates to overgaiters and the object thereof is to provide a gaiter of this class which is readily adaptable to use with or without the usual rubber foot coverings, commonly known as galoshes; a further object being to provide a gaiter of this 15 class which is similar in appearance to gaiters as constructed at present when used without the said foot coverings, and which is not only neat in appearance, but very inexpensive in manufacture.

20 My invention is fully described in the following specification, of which the accompanying drawings form a part, in which the separate parts are designated by the same 25 reference characters in each of the views and in which:

25 Figure 1 is a view of a shoe provided with my gaiter. Fig. 2 is a similar view, but with the gaiter opened in order to more clearly 30 set forth the construction. Fig. 3 a sectional view showing the gaiter in use upon a shoe without the rubber foot covering, and Fig. 4 a view similar to Fig. 3, but showing the 35 gaiter in position when the foot coverings are employed.

35 In the drawings forming a part of this application, I have shown a gaiter *a* placed upon a shoe *b*, said gaiter comprising a rear member *c* and a front member *d*, adapted to 40 be connected as shown at *e* by means of the usual glove fasteners, buttons or other equivalents.

45 Permanently connected with each side of the gaiter and adjacent to the bottom thereof as shown at *f* is a strap *g*, which passes underneath the shoe *b* and is preferably provided with a buckle *h* to connect the two parts of the strap *g*, but the said strap may be composed of elastic material, in which 50 event the buckle *h* is dispensed with.

Secured in the bottom of the front member *d* of the gaiter and at each side thereof is the female member *h* of the usual glove fastener, and secured at a corresponding point to the 55 strap *g* and at each side of the gaiter is the

male member *i* of the said fastener; and when my gaiter is employed in connection with a shoe, but without the rubber foot covering, the members *h* and *i* of the glove fastener are connected with each other, thereby forming a substantially integral construction, which serves to hold the bottom of the gaiter close to the shoe upon which it is placed.

When it is desired to use the overgaiter in connection with a rubber foot covering, the members *h* and *i* of the fastener are disconnected, the strap *g* is passed beneath the foot in the usual manner, after which the foot covering *k* is placed over the shoe, the sides 70 of the gaiter being raised to permit this operation; and when the overshoe *k* is in position, the sides of the gaiter are dropped over the upper edges of said overshoe as clearly shown in Fig. 4, and thereby a neat 75 effect is produced, and it will be seen that the strap *g* is inside of the said foot covering, while the gaiter itself is outside of the same.

Although I have shown a glove fastener for the purpose of holding the strap *g* and 80 sides of the gaiter together, it will be obvious that ordinary buttons may be employed, and various other changes in, and modifications of the construction shown and described may be made within the scope of the following 85 claims, without sacrificing the advantages of my invention or departing from the spirit thereof, and with this reservation,

What I claim as new and desire to secure by Letters Patent is:—

1. A gaiter, comprising a front and rear member adapted to be connected with each other, a strap secured to said gaiter, at each side thereof, and at a predetermined distance from the lower edge and supplemental devices for detachably connecting said strap to the lower edge of said gaiter, at each side thereof.

2. A gaiter comprising a front and rear member adapted to be connected with each other, a strap permanently connected to said gaiter at one side thereof and at a predetermined distance from the lower edge thereof, a supplemental strap similarly secured to the other side of said gaiter, devices for connecting said straps with each other and means for detachably connecting the lower edge of said gaiter with said straps.

3. A gaiter comprising a front and rear member adapted to be connected with each

other, a strap permanently secured to said gaiter at each side thereof, and at a predetermined distance from the lower edge thereof, a securing device comprising two members, one of which is secured to said strap and the other of which is secured to said gaiter at each side thereof.

5 In testimony that I claim the foregoing as

my invention I have signed my name in presence of the subscribing witnesses this 18th 10 day of March 1907.

HYMAN COHEN.
